UNITED STATES PATENT OFFICE.

BENJAMIN S. WHITEHEAD, OF NEWARK, NEW JERSEY, ASSIGNOR TO THE WHITEHEAD & HOAG COMPANY, OF NEW JERSEY.

DEVICE FOR DISPLAYING PHOTOGRAPHS, PICTURES, &c.

SPECIFICATION forming part of Letters Patent No. 634,156, dated October 3, 1899.

Application filed June 1, 1898. Serial No. 682,251. (No model.)

To all whom it may concern:

Be it known that I, BENJAMIN S. WHITEHEAD, a citizen of the United States, residing at Newark, in the county of Essex and State of New Jersey, have invented certain new and useful Improvements in Devices for Displaying Photographs, Pictures, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My present invention is in the nature of improvements on my previous invention in devices or holders for displaying a photograph, picture, medallion, or the like, for which Letters Patent No. 607,104 were granted to me and dated July 12, 1898.

My present invention therefore has for its primary object to provide an improved construction of photograph, picture, or medallion holder, which shall be of a simple and cheap construction and is of a very ornamental character, and by the application of a suitably-constructed pin may also be used as a badge to be worn on the lapel of a garment.

The invention therefore consists generally in the arrangement of a shell having an annular and inwardly-turned rim bearing a picture, design, emblem, or other suitable device, and an ornamental frame-like device having a recessed or chambered portion in which the shell is arranged, and said portion having radially-disposed lugs or tongues which extend toward the center of the picture-bearing shell and are turned back upon themselves and directly over the inwardly-turned rim of said shell, whereby the several parts are securely held in proper relation to each other.

The invention furthermore consists in the combination of such shell, bearing a picture, design, emblem, or other suitable device, having an annular bead or rim which forms a recessed or chambered portion in the back of said shell, with an ornamental frame-like device adapted to receive said shell, and a pin

in suitable holding arrangement in the chambered part of said shell, whereby the whole device may be used as a badge.

The invention is clearly illustrated in the accompanying drawings, in which—

Figure 1 is a front or face view of my novel form of photograph, picture, or medallion holder; and Fig. 2 is a back view of the same provided in addition with a pin, whereby the device may be used as a badge. Fig. 3 is a cross-section of the device, taken on line 3 3 in said Fig. 2; and Fig. 4 is a similar section taken on line 4 4 in said Fig. 2. Fig. 5 is a back view of the ornamental frame which is employed in connection with the photograph or picture bearing shell or medallion; and Fig. 6 is a similar view of said shell or medallion before insertion in the ornamental frame. Fig. 7 is a back view of an ornamental frame to be used in connection with the said shell, said frame being of a slightly-modified form of construction.

Similar letters of reference are employed in all of the above-described views to indicate corresponding parts.

In said drawings, *a* indicates a suitably-curved metallic shell, which is formed with an inwardly-projecting marginal rim or bead *a'*, thereby forming a chambered portion *a*² in the back of said shell, as clearly illustrated in Figs. 2, 3, 4, and 5. Upon the face of this shell I prefer to arrange a flexible disk or covering *a*³, of celluloid, paper, or any other suitable material, usually provided with a photograph or other desirable picture, insignia, emblem, or design. The annular edge of said disk or covering *a*³ is arranged over and underneath said marginal rim or bead *a'* of the shell *a*, where it is held fast and pulled taut by a suitable ring or collet *b*, as clearly illustrated in said Figs. 3 and 4. The said ring or collet *b*, which is provided with an inwardly-extending annular rim or edge *b'*, is arranged against the inner edge of said marginal rim or bead *a'* of the shell *a* and holds a suitable stiffening-disk *a*⁴, of paper or other material, in place in the said chamber *a*². Of course it will be evident that the said disk *a*⁴ is not essential to the present construction and may be dispensed with, if desired. The said annular rim *b'* of the said collet *b* also

forms a receiving portion for the holding portion c' of a suitable pin or bar c . Said pin or bar is usually made from a continuous piece of wire of any desirable size or shape in cross-section and is formed with the pointed end c^2 and with the semicircular curved holding portion c' above mentioned. Said holding portion c' is connected with the main bar or pin c by means of the two looped or curved parts c^3 and c^4 , which are bent in a plane at a right angle to the plane of said curved portion c' , and are practically in the same vertical plane passing through the longitudinal central axis of the said pin or bar c . Said curved holding portion c' is readily engaged in said ring or collet b in the chambered portion of the shell a during the assembling process of the several parts of the medallion, or the said holding portion of said pin can be directly sprung into position in said ring or collet b , or it may be otherwise secured to the said shell a , as will be clearly evident. When the said portion c' of the pin c has been fitted in the said ring or collet b , then the said curved part c^3 will extend around the annular edge b^2 of said ring b , and the curved part c^4 will extend considerably back of the outer surface of said edge b^2 , whereby the bar or pin c will stand in a position considerably away from the back of the medallion a , as clearly indicated in said Figs. 3 and 4.

As will be seen from the several figures of the drawings, said shell or medallion a , bearing the photograph, picture, or the like, is used in connection with an ornamental frame-like device e , which may be of any desirable configuration in outline, and may be highly ornamented. The said frame-like device, which is made of metal, is provided with a centrally-arranged depression e' , formed by the backwardly-extending annular part e^2 and the flat ring-shaped edge e^3 , said ring having holding-prongs e^5 , as illustrated in Figs. 2, 3, 4, and 5, or it may be provided with a solid or closed back e^4 , as indicated in said Fig. 7, in which latter case the prongs e^5 are forced directly out from the solid back e^4 and then bent in the manner to be hereinafter set forth. These said parts form a suitable chamber in the frame-like device e , into which the shell or medallion a , hereinabove mentioned, can be placed and retained therein by any suitable number of said holding prongs or lugs e^5 , which extend in radial lines toward the center of said frame-like device, and by means of a proper tool can be forced into the chamber a^2 of the shell or medallion a and then bent back and down against the holding portion c' of the pin or bar c or against the annular edge b^2 of the said ring or collet b , as will be clearly understood from an inspection of Figs. 2 and 4. To facilitate the perfect arrangement of the medallion a in the said frame e and also to prevent the turning of the pin or bar c in connection with the said medallion and frame, I have provided the ring-shaped edge e^3 of the frame e at the desired point with a suitable

slot or cut-away part, as e^6 , as indicated in Figs. 2 and 5, or, where the closed back e^4 is used, with a hole or opening e^7 , (see Fig. 7,) in which the curved part c^1 of the pin c is arranged in such a manner that the pin or bar c will become arranged on the back and outer surface of the said frame e , with the said curved part c^4 securely lodged in either the said slot or cut-away part e^6 or the said hole e^7 to prevent any possible turning or displacement of the said parts. The said frame-like device e is usually provided with a suitably-curved lip e^8 , as indicated in Figs. 3 and 5, or with a similar lip e^9 , as in Fig. 7, which is formed integral with the main body of said frame-like device e and forms a receiving portion for the pin-point c^2 of the said pin or bar c after it has been forced through the garment, whereby when the device is used as a badge it becomes securely attached to the garment and cannot be brushed off or become detached in any other manner and lost.

From the above description it will be seen that I have devised a simple and cheap as well as an ornamental and useful device, which can be put to many different uses.

Having thus described my invention, what I claim is—

1. In a device for displaying photographs, pictures, medallions, &c., the combination, with an ornamental frame-like device, having a central depression formed therein, of a shell having an inwardly-extending annular rim or bead, arranged in said depression, a collet in said shell held therein by said rim or bead, and radially-disposed holding lugs or prongs on said frame-like device, said lugs or prongs being bent back upon themselves and clamped down upon the inner surface or edge of said collet, substantially as and for the purposes set forth.

2. In a device for displaying photographs, pictures, medallions, &c., the combination, with an ornamental frame-like device, having a central depression formed therein, of a shell having an inwardly-extending annular rim or bead, arranged in said depression, a ring or collet having an inwardly-extending annular edge extending into the back of said shell and held therein by said annular rim or bead of said shell, a flexible covering on said shell, bearing a picture, emblem, design, or the like, and radially-disposed holding lugs or prongs on said frame-like device, said lugs or prongs being bent back upon themselves and clamped down upon the inner surface or edge of said collet, substantially as and for the purposes set forth.

3. In a device for displaying photographs, pictures, medallions, &c., the combination, with an ornamental frame-like device, having a central depression formed therein, of a shell having an inwardly-extending annular rim or bead, arranged in said depression, a collet in said shell held therein by said rim or bead, and radially-disposed holding lugs or prongs on said frame-like device, said lugs or prongs

being bent back upon themselves and clamped down upon the inner surface or edge of said collet, and a pin or bar connected therewith, substantially as and for the purposes set forth.

5 4. In a device for displaying photographs, pictures, medallions, &c., the combination, with an ornamental frame-like device, having a central depression formed therein, of a shell having an inwardly-extending annular 10 rim or bead, arranged in said depression, a ring or collet having an inwardly-extending annular edge extending into the back of said shell and held therein by said annular rim or bead of said shell, a flexible covering on said shell bearing a picture, emblem, design, or the like, and radially-disposed holding lugs or prongs on said frame-like device, said lugs or prongs being bent back upon themselves and clamped down upon the inner surface or 20 edge of said collet, and a pin or bar connected therewith, substantially as and for the purposes set forth.

5. In a device for displaying photographs, pictures, medallions, &c., the combination, with an ornamental frame-like device *e*, having a central depression formed by a backwardly-extending portion of said frame-like device, and also having a slot or opening in said portion, of a shell having an inwardly-extending annular rim or bead, arranged in said depression, and a pin or bar *c*, having a holding portion *c'*, and a connecting curved or looped part *c*⁴ fitted into the said slot or opening in said frame portion and held therein, substantially as and for the purposes set forth.

6. In a device for displaying photographs, pictures, medallions, &c., the combination, with an ornamental frame-like device *e*, having a central depression formed by a backwardly-extending portion of said frame-like device, and also having a slot or opening in said portion, of a shell having an inwardly-extending annular rim or bead, arranged in said depression, a ring or collet having an inwardly-extending annular edge extending into the back of said shell and held therein by said annular rim or bead of said shell, a flexible covering on said shell, bearing a picture, emblem, design, or the like, radially-disposed holding lugs or prongs on said frame-like device, said lugs or prongs being bent back upon themselves and clamped down upon the inner surface or edge of said collet, and a pin or bar *c*, having a holding portion *c'*, and a connecting curved or looped part *c*⁴ fitted into the said slot or opening in said frame-like portion and held therein, substantially as and for purposes set forth.

the said slot or opening in said frame-like portion and held therein, substantially as and for the purposes set forth.

55

7. In a device for displaying photographs, pictures, medallions, &c., the combination, with an ornamental frame-like device *e*, having a central depression formed by a backwardly-extending portion of said frame-like device, and also having a slot or opening in said portion, of a shell having an inwardly-extending annular rim or bead, arranged in said depression, a collet in said shell held therein by said rim or bead, radially-disposed holding lugs or prongs on said frame-like device, said lugs or prongs being bent back upon themselves and clamped down upon the inner surface or edge of said collet, and a pin or bar *c*, having a holding portion *c'*, and a connecting curved or looped part *c*⁴ fitted into the slot or opening in said frame-like portion and held therein, substantially as and for the purposes set forth.

70

8. In a device for displaying photographs, pictures, medallions, &c., the combination, with an ornamental frame-like device *e*, having a central depression formed by a backwardly-extending portion of said frame-like device, and also having a slot or opening in said portion, of a shell having an inwardly-extending annular rim or bead, arranged in said depression, a ring or collet having an inwardly-extending annular edge extending into the back of said shell and held therein by said annular rim or bead of said shell, a flexible covering on said shell, bearing a picture, emblem, design, or the like, radially-disposed holding lugs or prongs on said frame-like device, said lugs or prongs being bent back upon themselves and clamped down upon the inner surface or edge of said collet, and a pin or bar *c*, having a holding portion *c'*, and a connecting curved or looped part *c*⁴ fitted into the said slot or opening in said frame-like portion and held therein, substantially as and for purposes set forth.

85

In testimony that I claim the invention set forth above I have hereunto set my hand this 31st day of May, 1898.

BENJAMIN S. WHITEHEAD.
